No. 663,511.

Patented Dec. 11, 1900.

W. S. PACA.

TELEPHONE SWITCHBOARD APPARATUS.

(Application filed Feb. 16, 1900.)

(No Model.)

UNITED STATES PATENT OFFICE.

WILLIAM S. PACA, OF ERIE, PENNSYLVANIA, ASSIGNOR OF ONE-HALF TO
PETER H. ADAMS, OF SAME PLACE.

TELEPHONE-SWITCHBOARD APPARATUS.

SPECIFICATION forming part of Letters Patent No. 663,511, dated December 11, 1900.

Application filed February 16, 1900. Serial No. 5,463. (No model.)

To all whom it may concern:

Be it known that I, WILLIAM S. PACA, a citizen of the United States, residing at Erie, in the county of Erie and State of Pennsylvania, have invented certain new and useful Improvements in Telephone-Switchboard Mechanism; and I do hereby declare the following to be a full, clear, and exact description of the invention, such as will enable others skilled in the art to which it appertains to make and use the same, reference being had to the accompanying drawings, and to the letters and figures of reference marked thereon, forming part of this specification.

My invention relates to improvements in multiple-switchboard mechanism, and is designed to facilitate the testing of the lines by the operators to find out whether a subscriber's line called for is in use. A multiple switchboard is ordinarily composed of a plurality of boards or sections, to each of which the lines of all of the subscribers are branched or connected, so that the operator at any board or section can connect up any two lines desired; but if one of the lines desired has been already connected up at another board or section the plugging in of another operator on one of the lines so connected up creates an interruption or disturbance of the lines so in use. Heretofore many types of mechanism have been devised for the purpose of testing the lines to find out whether they are in use before plugging in upon them, some of which mechanisms are in common use, an example of which is the so-called "click-signal," the operation of which is well understood.

In my invention I have done away with many of the difficulties common to the busy-test systems now in use and simplified the construction of the mechanism, by means of which my busy test can be operated so that the operator at any board or section can at once determine whether any line desired is in use without in any degree interfering with or interrupting such use. I accomplish this result by connecting the frames of the jacks forming the terminals of each line on all of the boards or sections to one side of a local-battery circuit having resistance-coils there-

in and make the switch-plugs with a coil connected to the other side of said local-battery circuit and also to the point of the switch-plug, so that when a plug is inserted in any one jack of a series the circuit is closed, so 55 that by touching the point of another switch-plug to any other jack of said series so plugged in upon a circuit is completed through the coil in the plug to the point thereof and thence through the jack-frame 60 touched, so that the point of the plug becomes magnetized and adheres to the frame of the jack so touched, thereby indicating that the line with which said jack is connected is in use. These and other features 65 of my invention are hereinafter set forth and explained, and illustrated in the accompanying drawings, in which—

Figure 1 is a diagrammatic view of a portion of a multiple switchboard embodying 70 my invention. Fig. 2 is a sectional view of a jack and switch-plug forming part of my invention.

In Fig. 1 the numerals 1 and 2 designate two subscribers' telephone apparatus, and the numerals 1' and 2' designate portions of the operator's apparatus at two sections of a multiple switchboard, and the drawing further illustrates telephones Nos. 1 and 2 connected up and in use, while the operator at station 2' is 75 testing to find out whether the line leading to telephone No. 2 is in use. Referring further to the drawings, at station 1' I show an operator's switch and telephone A, ring-off drop A', and magneto A², which are of the 80 usual construction, as are the connections f¹ to the switch-plug F and the connections F³ and f⁵ to the switch-plug F', and at station 2' a portion of the same mechanism is shown, together with a switch-plug F² and its connections at station 2'. These features are, 85 however, of the usual and ordinary construction and operation.

The line a from telephone No. 1 extends to line a', which by branches a² connect with 90 the insulated collars b (see Fig. 2) of the series of jacks B, which collars are adapted to receive and contact with the stems of switch-plugs F, inserted therein. The line C from telephone 95 No. 1 extends to and is connected by the line 100

c' through a drop-magnet D and by a branch *d* with the armature *e* of an ordinary relay E in the usual manner, and thence by line *c*² to line *c*³, and from thence by branch lines *c*⁴ to the tongues *b'* of the series of jacks B, so that when the stem of the switch-plug F is inserted in the collar *b* of one of the series of jacks B it operates to connect the line *f*, leading from station 1' through the collar *b*, with the line *a*², and thence through the lines *a'* and *a* to telephone No. 1, and through line *f'* and tongue *b'* to the lines *c*⁴ and their connecting lines directly to telephone No. 1.

From telephone No. 2 the line *h* extends to 15 a line *h'* and thence by branch lines *h*² to the insulated collars *b* in the series of jacks B', which collars are adapted to receive and contact with the stems of switch-plugs F', inserted therein, and the line H from telephone 20 No. 2 extends to and connects by the line H' through a drop-magnet D' and by a branch *d'* with the armature *e'* of an ordinary relay E' in the usual manner, and thence by the line H² to the line H³, and thence by branch lines 25 H⁴ to the tongues *b'* of the series of jacks B', so that when the stem of the switch-plug F' is inserted in the collar *b* of one of the series of jacks B' it operates to connect the switch-plug line *f*³, leading from station 1' through 30 the collar *b*, with the line *h*², and thence through lines *h'* and *h* to telephone No. 2, and by switch-plug line *f*⁴ through the jack-tongue *c'*, and through the line H⁴ and their connecting lines directly with telephone No. 2. These 35 features are of the usual construction and arrangement in use in multiple switchboards and are shown in connection with the novel switch-plug and local-battery circuit hereinafter described.

40 The local-battery circuit comprises a local battery G with lines *g* and *g'* leading therefrom, the line *g* extending to and connecting by means of a branch line *g*² with the lines *f*², *f*⁵, and *f*⁶ of the switch-plugs F F' F², as 45 and for the purpose hereinafter set forth, and also through resistance-coils G' and lines *g*³ and branch lines *g*⁴ with the frames of the series of jacks B and B', the resistance-coils G' operating to sufficiently resist the travel of 50 the current toward the line *g* on its return to battery G to cause it to traverse the branch lines *g*⁴ and the frames of the series of jacks B B' before it passes the resistance-coils G' on its way back to the battery G. To the 55 jack-tongues *b*² are connected branch lines *g*⁵, which join lines I, leading to and connected with lines I² and I', which lead to the relays E and E', while the line *g'* from the battery G connects with the relay E and by a branch *g*⁶ 60 with the relay E', so that when the switch-plugs F and F' are inserted in the jacks B or B' a circuit is formed from the battery G through the contact of the jack-tongues *b*² with the lugs *b*³ on the jack-frame through 65 the wires I and *g*³ and wires I² or I' through the relay E or E' to the wire *g'*, and back to the battery G.

The switch-plugs F, &c., are constructed (see Fig. 2) with a point of magnetic metal L, which is insulated from the remainder of the 70 plug by insulation l, and adjacent to the insulation l is a coil L', one end of which, l', connects with the point L and the other with the stem M of the plug—say at *m*. This stem connects with wire *f*², leading to the local battery line *g*², and is insulated from the bearing M', which connects with the line *f*¹, leading to the operator's switch mechanism 1', and is adapted to contact with the jack-tongue *b'*, surrounding the stem M' of the bearing M', 80 and insulated therefrom by insulation n is a shell N, adapted to contact with the insulated collar *b* in the jack B, and leading therefrom is a line *f*, connecting with the operator's switch mechanism. Through the line *f*⁶, connecting with the line *g*² of the local-battery circuit, when the point L of a plug is brought into contact with the end of one of the jacks B', as illustrated by plug F², connected with operator's set No. 2, if a switch-plug, as F', 90 is inserted in one of the series of B', a connection is made between the point L of the plug and the jack-frame connected with the opposite side of the local circuit, which excites the coil L', so as to magnetize the point 95 L of the plug, which causes it to adhere to the jack so touched, showing that the subscriber's line connected with such jack is in use; but if the plug F' is not inserted in the jack, as shown, then no circuit will be set up, 100 and as the point of the plug is not then magnetized it does not adhere to the jack touched thereby, which indicates to the operator that the line is not in use.

The jack B or B' is constructed of soft iron 105 or other magnetic metal and is provided with an opening for the insulation of the switch-plug, which is lined with a metal collar *b*, which is insulated from the remainder of the jack and connected with the lines *a*² or *h*², as 110 the case may be, while to the rear end of the jack are secured contact-tongues *b*¹ and *b*², insulated from each other and from the jack-frame, and on the jack-frame there is a contact-point *b*³, adapted to connect the tongue 115 *b*² when the switch-plug is in place, as clearly shown in Fig. 2. The operation of these parts, together with the parts of the switch-plug, in connection with the telephonic and local circuits has been heretofore clearly explained, so that further description thereof is 120 deemed unnecessary.

I have thus shown and described a convenient mechanism and arrangement of circuits for utilizing my invention; but I do not desire to confine myself to the exact construction and arrangement herein shown and described, as I am aware that both the mechanism and its arrangement may be considerably modified without departing from the 130 spirit of my invention. Therefore

What I claim as new, and desire to secure by Letters Patent of the United States, is—

1. In a multiple switchboard, the combina-

tion of two or more duplicate sections, jacks forming terminals for each subscriber's line on each of said sections connected up in open circuit with a local battery, switch-plugs 5 adapted, when inserted in any jack of a series, to connect a subscriber's circuit, and also connect with one side of the local circuit all the jacks of the series so plugged upon, and a coil in the switch-plug connected with one 10 side of the local-battery circuit and adapted to complete such local circuit through any jack of the series plugged in upon, by bringing the tip of such plug into contact therewith, whereby the point of such plug becomes 15 magnetized, substantially as and for the purpose set forth.

2. A switch-plug for telephone-switchboards, comprised, substantially, of a coil connected at one end with a local-battery circuit 20 and at the other with an insulated tip of magnetic metal and adapted, when said tip is brought into contact with the other side of said local-battery circuit, to become magnet-

ized, substantially as and for the purpose set forth.

3. The combination of a jack for telephone-switchboards connected with one side of a local-battery circuit, a switch-plug having a coil connected with the other side of said local-battery circuit and a tip of magnetic metal 25 on said plug connected with said coil and adapted, when any one jack of a series is plugged in upon, to be brought into contact with any other jack of the series so plugged in upon and complete the circuit through said 30 jack-frame with the local battery, whereby the tip of the plug becomes magnetized and adheres to the jack so touched, substantially as and for the purpose set forth.

In testimony whereof I affix my signature 40 in presence of two witnesses.

WILLIAM S. PACA.
